J. N. WHITEHOUSE,
METHOD OF MAKING CELLULOID TUBES.
APPLICATION FILED FEB. 9, 1914.

UNITED STATES PATENT OFFICE.

JOHN NATZI WHITEHOUSE, OF NEWARK, NEW JERSEY.

METHOD OF MAKING CELLULOID TUBES.

1,125,893.

Specification of Letters Patent.

Patented Jan. 19, 1915.

Application filed February 9, 1914. Serial No. 817,542.

To all whom it may concern:

Be it known that I, JOHN N. WHITEHOUSE, a citizen of the United States, residing at Newark, in the county of Essex and State 5 of New Jersey, have invented certain new and useful Improvements in Methods of Making Celluloid Tubes, of which the following is a specification.

This invention relates to celluloid tubes 10 such as are useful for fountain-pen caps and barrels like those shown in my Patent No. 836,905, granted November 27th, 1906, and to the method of manufacturing such tubes.

The characteristic features of the tube 15 made in accordance with this invention will be clear from the specification, and the method employed in making it will appear from the following description of the various steps thereof, while the scope of protection contemplated will appear from the claims.

In the accompanying drawing, which is to be taken as a part of this specification, and in which I have shown a preferred form 25 of embodiment of the tube constituting the invention, and in which I have also indicated the method of manufacture: Figure 1 is a longitudinal section showing a sheet of celluloid material in position within an outer cylindrical former, whereby the sheet is given a tubular form. This view is taken on the line 1—1 of Fig. 2; Fig. 2 is a transverse section taken on the line 2—2 of Fig. 1; Fig. 3 is a view similar to Fig. 1, indicating the softening of the abutting edge 30 portions of the celluloid sheet within the cylindrical former, this view being taken on the line 3—3 of Fig. 4; Fig. 4 is a transverse section on the line 4—4 of Fig. 3, and shows 35 also how the abutting edges of the celluloid sheet are positively urged toward each other; Fig. 5 is a view, similar to Fig. 3, showing the reinforce strip in place over the abutting edge portions of the celluloid sheet 40 within the cylindrical former, this view being taken on the line 5—5 of Fig. 6; Fig. 6 is a transverse section on the line 6—6 of Fig. 5; and Fig. 7 is a perspective view, partly broken away, illustrating the mode 45 of applying the reinforce member to the abutting edges of the celluloid strip after the latter has been given its tubular form.

Referring to the numerals on the drawings, the method of making the tube will be 5 described, and from this a clear understanding may be had of the characteristic features

of the tube. Accordingly, I provide a cylindrical former indicated by the numeral 8. I next take a sheet of celluloid or other suitable material indicated by the numeral 9 of proper width and of length not greater than that of the cylinder, and insert the same within the former 8 as shown in Figs. 1 and 2. As stated, the sheet is cut of the proper width so that when it is placed within the cylindrical former the longitudinal edges 10 thereof will abut. Next I take a rod 11 of suitable diameter and insert it longitudinally between the inner wall of the cylindrical former and the outer face of the celluloid sheet 9, so that said rod will lie substantially opposite the line of the abutting edges 10. The effect of thus introducing the rod 11 is to urge the abutting edges 10 of the celluloid sheet positively toward each other, so that when I proceed to soften 65 the inner edge portions of the celluloid sheet, as by passing over them a brush carrying a suitable solvent, the softened edge portions will be merged into one another under the 70 continued pressure produced by the rod 11. I have indicated the area of softening by the reference character 12 in Figs. 3 and 4.

The result of the operations thus far described will obviously be to weld together 85 the abutting edges of the celluloid sheet, so that a tube will be formed. But obviously the tube is apt to be weak along the line of the weld, and in order to strengthen it at this point, I propose to cover the tube 90 interiorly over the abutting edge portions with a reinforce strip 14, which may be of silk or other suitable material. And in order to insure that the reinforce strip shall become practically an integral part of the 95 tube, I propose to force the strip down into the abutting edge portions while these portions are still soft from the solvent. This may be accomplished, for instance, by placing the strip in the tube while the latter is 100 still within the cylindrical former, over the softened edge portions, with the ends of the strip projecting out of the ends of the tube. If both ends of the strip are now simultaneously drawn down, or if one end 105 is held and the other end drawn down, the result will be of course to force the whole length of the strip inside the tube down into the softened edge portions of the tube, so that the softened celluloid material will be 110 driven into the interstitial spaces of the silk reinforce strip, and the abutting edges of

the sheet will be thoroughly amalgamated with each other and with their common reinforcing strip. The longitudinal rod 11 is now withdrawn, whereupon the completed tube may be readily taken out of the cylindrical former. In order that the withdrawal of the completed tube may be as easy as possible, and in order to avoid sticking thereof within the cylindrical former, I prefer that at the outset the celluloid sheet shall be of such width that when it is inserted into the cylindrical former as shown in Fig. 2, and springs into face-contact with the interior of the cylindrical former, that the edges 10 shall not be in contact. Thus when the member 11 is introduced, the edges 10 are driven together and the tube, after the edges have been joined together, will be of sufficiently 20 smaller diameter than the cylindrical former so that it may be easily withdrawn.

It is to be understood that material, sizes and relations of parts are unimportant except as set out in the claims. And obviously 25 there may be many changes in the character and sequence of the steps of operation described, without departing from the spirit of the invention.

I claim:—

30 1. The method which consists in providing a cylindrical former, inserting within the same a sheet of celluloid material or the like of suitable width and length so that when the same is sprung against the inner 35 walls of the cylindrical former it will assume a tubular form with its edges in adjacency, deforming the celluloid tube thus formed within the cylinder so as to urge the adjacent edges thereof into contact and holding it temporarily so deformed, softening

the edge portions of the tube thus deformed, overlaying the edge portions with a reinforcing strip of silk or the like, and driving said strip down into the celluloid material so as to form a unitary structure, 45 causing the previously softened material of the edge portions to harden after the edges have coalesced with each other and with the reinforcing strip, permitting the tube to assume its natural shape, and withdrawing it 50 from the cylindrical former.

2. The method which consists in providing a cylindrical former, inserting within the same a sheet of celluloid material or the like of suitable width and length so that 55 when the same is sprung against the inner walls of the cylindrical former it will assume a tubular form with its edges in adjacency but out of contact, deforming the celluloid tube thus formed within the cylinder so as to urge the adjacent edges thereof into contact and holding it temporarily so deformed, softening the edge portions of the tube thus deformed, overlaying the edge 60 portions with a reinforcing strip of silk or the like, and driving said strip down into the celluloid material so as to form a unitary structure, causing the previously softened material of the edge portions to harden after the edges have coalesced with 65 each other and with the reinforcing strip, permitting the tube to assume its natural shape, and withdrawing it from the cylindrical former.

In testimony whereof I affix my signature in presence of two witnesses.

JOHN NATZI WHITEHOUSE.
